BOILER CLEANER

Leo J. Bayer, St. Louis, Mo.

Application January 12, 1935, Serial No. 1,527

7 Claims. (Cl. 122—392)

My invention has relation to improvements in boiler cleaners, and it consists in the novel features of construction more fully set forth in the specification and pointed out in the claims.

5 The invention is primarily directed to that type of boiler cleaner wherein a blower tube, provided with longitudinally disposed nozzles, is disposed across a bank of boiler tubes and arranged for rotation so that steam may be directed to different parts of the boiler to remove deposits from the boiler tubes. That part of the blower containing the valve mechanism for controlling the discharge of steam against the boiler surfaces is generally referred to as the head and has associated with it mechanism for rotating the blower tube. Heretofore, two types of blowers have been most commonly used, the one having the valve actuating mechanism and the blower rotating mechanism completely separated, requiring two 10 distinct operations by the operator to perform the cleaning of the boiler, and the other having a valve and blower tube actuating mechanism interconnected so that on the operation of one the other will be automatically operated. This 15 second type, sometimes referred to as the automatic valve type, requires for its use but a single operation by the operator.

It is the object of the present invention to provide a boiler cleaner in which the valve actuating mechanism and the blower tube rotating mechanism are independent but at the same time are operated from a single actuating means which is moved in one direction to actuate the valve and in the opposite direction to rotate the 20 blower tube.

The advantage of my improved blower operating means is that the valve may be opened or closed at any time desired and any arc of rotation of the blower tube may be obtained while the valve is fully opened to permit steam to issue from the blower tube for the cleaning of the boiler. A further advantage is that the cleaning efficiency of an independently operated valve blower is obtained without the necessity of a separate actuating means. This simplifies the work of the operator as the entire blowing operation is performed by the manipulation of but a single operating chain. These advantages and 25 their manner of accomplishment will be better apparent from a detailed description of the invention in connection with the accompanying drawings, in which:

Figure 1 is a front elevation of my improved boiler cleaner; Fig. 2 is a side elevation of the

head thereof and the actuating mechanism mounted on said head, the blower tube and steam supply pipe being broken away; Fig. 3 is a vertical, middle, longitudinal section taken on the line 3—3 of Fig. 1; Figs. 4, 5, 6 and 7 are enlarged 5 horizontal cross-sectional details taken on planes indicated by the lines 4—4, 5—5, 6—6 and 7—7, respectively, in Fig. 3; Fig. 8 is a sectional detail similar to that of Fig. 7 except that the parts are shown in position to open the steam 10 supply valve while in Fig. 7 the parts are shown in position when said valve is closed; Fig. 9 is a vertical, transverse section taken on a plane indicated by the line 9—9 of Fig. 3; Fig. 10 is an enlarged sectional detail of the inner end of the 15 movable stop and cooperating lug fixed on the driving gear for the boiler tube; Fig. 11 is an enlarged horizontal section taken on a plane indicated by the line 11—11 in Fig. 3; Fig. 12 is an enlarged vertical, cross-sectional detail taken 20 on a plane indicated by the line 12—12 in Fig. 3; Fig. 13 is a view similar to that of Fig. 12 showing the parts moved through a 90° arc, the first step in the operation of the blower; Fig. 14 is a side elevation of the ratchet wheel shown 25 in Fig. 12 obtained by a projection of said figure; Fig. 15 is also a side elevation of the ratchet wheel shown in Fig. 12, the view being obtained at an angle of 90° from that of Fig. 14; Fig. 16 is a horizontal sectional detail taken on a plane indicated by the line 16—16 in Fig. 3; Figs. 17 and 30 18 are plan and side elevations, respectively, of the driving cylinder for the shaft which actuates the blower tube; Fig. 19 is a diagrammatic 35 view of the associated parts showing said parts for the at rest position of the blower; Fig. 20 is a diagram of the same parts showing their position when the operating chain has been pulled to open the steam valve but before the blower 40 tube has been rotated; Fig. 21 is a diagram of said parts showing their respective positions after the operating chain has been pulled to rotate the blower tube to the end of its blowing arc; Fig. 22 is a diagram of said parts showing their 45 respective positions after the steam valve has been closed and before the blower tube has been restored to its original position; Fig. 23 is a diagram showing said parts during the rotation of the blower tube to its starting position so that 50 it will be in condition for the next subsequent blowing operation; Fig. 24 is a combined side elevation and middle, vertical longitudinal section of a modified form of actuating mechanism embodying the principles of the present invention. 55

tion; Figs. 25, 26 and 27 are vertical, sectional details taken on the planes indicated by the lines 25—25, 26—26 and 27—27, respectively, in Fig. 24; Fig. 28 is a section similar to that shown in Fig. 27, except that the parts have been moved to show the valve stem depressed to open the steam valve; Fig. 29 is a vertical, cross-sectional detail taken on a plane indicated by the line 29—29 in Fig. 23; Fig. 30 is a combined top plan and horizontal section taken on the line 30—30 in Fig. 24; Fig. 31 is a vertical, cross-section taken on the line 31—31 in Fig. 24; Fig. 32 is a vertical, cross-sectional detail taken on the line 32—32 in Fig. 24; and Fig. 33 is a diagrammatic view of the stop bars showing their association with the operating chain wheel and gear for rotating the blower tube.

Referring to the drawings, B indicates the wall of a boiler on which my improved boiler cleaner is mounted. According to established practice, a hollow casing 1, known as a wall sleeve, is fixed in an opening O of the boiler wall and a supporting member 2 is secured by suitable bolts 3 to a flange 4 formed on the wall sleeve 1. The supporting member 2 forms no part of the present application as it forms the subject-matter of a separate application for Letters Patent. However, some means must be provided for supporting the weight of the blower head 5 and bracket 6 mounted thereon for carrying the blower actuating mechanism, which is the subject of the present invention and is about to be described.

The blower head 5 comprises a stuffing box 7 and a valve casing 8, between which is a steam chamber 9 leading to a short pipe 10, which forms the connection between the steam chamber 9 and blower tube 11. The pipe 10 is rotatably mounted in the stuffing box 7 and a confining flange 12 depends from the bracket 6. In order that the joint between the rotatable pipe 10 and stuffing box 7 shall be steam-tight, suitable packing 13 is held in the stuffing box 7 by means of a gland 14. The head 5 is provided with a plain surface 15 above the stuffing box 7, on which the bracket 6 is securely held by means of suitable bolts 16, and a flange 17 is provided below the valve casing 8, to which is secured a second flange 18 in which the steam supply pipe 19 is threaded. A steam supply valve 20 is slidably mounted within the valve casing 8, and when in its closed position fits tightly on the valve seat 21 and has a stem 22 projecting upwardly through the top 23 of the valve casing, a coiled spring 24 being disposed over the stem 22 in engagement with an adjustable nut 25 thereon for the purpose of continually urging the steam upwardly in order to close said valve. The specific construction of the valve is of no importance so far as the present invention is concerned and will, therefore, not be described in further detail. The short pipe 10 and blower tube 11 are secured together by means of a combined gear 26 and coupling member 27, within the respective hubs 28 and 29 of which are threads to receive the threaded extremities 30 and 31 of said gear and coupling member.

Bolts 32 are passed through openings 33 and 34 evenly spaced around the hubs of the gear 26 and coupling member 27, and nuts 35 are tightly screwed on the threaded ends of the bolts to securely fix said gear and coupling member together in order that they may operate as a unit, and at the same time couple the short pipe

10 and blower tube 11 to each other and to the gear 26. Bearings 36 and 37 project upwardly from the ends of the bracket 6 and a shaft 38 is rotatably mounted in said bearings, the inner end of said shaft having a pinion 39 fixed on it, which pinion engages with gear 26 and serves to drive the same. The end of the shaft 38 projecting forwardly of the bearing 36 has mounted on it the actuating mechanism for both the valve 20 and blower tube 11. As we shall see in the description of the operation of the invention to follow, the pinion 39 and, of course, gear 26 are always rotated in the same direction, and in order to prevent accidental rotation in the wrong direction, when other parts of the blower are operated, a dog d is mounted on the inner projection 37' of bearing 37, the nose d' of said dog engaging the teeth of the gear 26 as shown (Fig. 9) to permit said gear to rotate only in one direction. Since the valve 20 must first be opened before the blower tube 11 can function, the mechanism whereby this valve is actuated must first be described.

A driving cylinder or disk 39' is fixed on the outer end of shaft 38 and a chain wheel 40 is rotatably mounted on said disk 39'. A ratchet wheel 41 (Figs. 5 and 12 to 15, inc.) is loosely mounted on the shaft 38 immediately inside the chain wheel 40 and in close proximity thereto so that its teeth 42 may be engaged by a pawl 43 mounted on a pin 44 fixed to the chain wheel 40. The pawl 43 is held in contact with the periphery of the ratchet wheel 41 by a coiled spring 45, one end of which is secured to the flange 46 of the chain wheel, and the other end secured to the back of the pawl 43 near the nose 43' thereof.

Immediately adjacent to the hub 47 of ratchet wheel 41 and loosely mounted on the shaft 38 is a second ratchet wheel 48 having four evenly spaced teeth 50 with which is integrally formed an elongated cam 51 having oppositely disposed flat faces 52, 52, which form the low sides of the cam, and oppositely disposed flat faces 53, 53 at right angles to the faces 52, which form the high sides of the cam. A pawl 54 is mounted on a pin 55 projecting from a boss 56, said pawl being disposed so as to engage the teeth 50 of the ratchet wheel 49. The cam 51 is positioned above the valve stem 22 and the outer end of a lever 57 is interposed between valve stem 22 and cam 51. The opposite end of the lever is pivotally mounted on a laterally extending bracket 58 projecting from the bearing member 36, said lever 57 being pivoted on a pin 59, the inner end of which is threaded to receive a nut 60. The parts just described constitute the valve actuating mechanism, the operation of which should be obvious. However, a brief description of such operation may not be amiss.

In order to open the valve 20 the operator pulls downwardly on the left side of the chain 61 disposed over chain wheel 41 so as to rotate said wheel to the left (Fig. 5). The pawl 43 will, of course, carry with it the ratchet wheel 41, and the pawl 54 in engagement with ratchet wheel 49 will also rotate this ratchet wheel and cam 51, which forms an integral part thereof. As the cam 51 rotates from the position shown in Fig. 7 to the position shown in Fig. 8 the lever 57 slides from the low side 52 of the cam to the high side 53 and is depressed to force the valve stem 22 downwardly and unseat the valve 20.

It is apparent that a rotation of the cam 51

through but 90° is sufficient to open the valve, at which time the rotation must be arrested. Suitable stop mechanism is provided for effecting the arrest of the valve actuating parts when the valve is fully opened. This stop mechanism comprises a rod 62 slidably mounted in openings 63 and 64 in the bracket member 6. The opening 63 is rectangular in shape to receive the flat terminal 65 on the outer end of rod 62, and the opening 64 has an enlarged cylindrical portion 66 to receive the terminal piece 67 and a coiled spring 68 nested between said terminal piece and shoulder 69 at the bottom of socket 66. The purpose of the spring 68 is to continually urge the rod 62 inwardly toward the gear wheel 26. The upper end of valve stem 22 passes through a lug 70 projecting forwardly from the bracket 6, on which the terminal 65 of rod 62 rests. Since the stem 22 must also pass through said terminal 65 in order to bear against lever 57 disposed thereabove, said terminal 65 is provided with a slot 71 to accommodate the valve stem and also to allow the rod 62 to slide backward and forward in a manner that will be described.

25 The ratchet wheel 41 has L-shaped lugs 72 and 73 projecting laterally from it, said lugs being spaced angularly slightly more than 90° , and the extremities 72' and 73' of the lugs rotating along an arc (when the ratchet wheel 41 is rotated) intersecting the end of lug 70 projecting forwardly from the bracket 6. Thus the rotation of the ratchet wheel 41 is limited to an arc of 90° , since lug 72 will strike the lug 70 at one end of said rotation arc and the lug 73 will strike the lug 70 at the other end of the rotation arc.

When lug 72 is in engagement with the lug 70 the valve will be closed and the blower tube at its position of rest, or the valve may be open and the blower tube in its position after having just completed the blowing operation, as will be more definitely explained in the description of the operation of the invention.

A flange 74 extends along an arcuate path from lug 73 toward lug 72 and encompasses an angle of slightly more than 90° , said flange having an inwardly turned cam surface 75, the forward edge 76 of which is inclined. A pin 77 projects upwardly from terminal 65 of rod 62 and is in operative engagement with the cam surfaces 75 and 76. The purpose of the cam surface 76 is to draw the rod 62 outwardly, and the purpose of the cam surface 75 is to hold the same in such position so that the terminal piece 67 at the inner end of rod 62 may be released from stop members 78 and 79 fixed in the gear 26, which stop members determine the arc of rotation of said gear and, of course, the blower tube 11. This will also become better apparent in the subsequent description of the operation of the invention.

60 The driving mechanism for actuating the blower tube 11 will now be described. The driving disk 39', as above stated, is fixed (in the present instance—keyed) to the shaft 38 and has a recess 80 opening on its periphery, in which recess is pivotally mounted a driving dog 81, the nose 82 of which is forced outwardly beyond the periphery of the disk 39' by spring pressed pin 83 which is lodged together with a coiled spring 84 in a socket 85 opening into the recess 80. The nose 82 of the dog 81 engages internal ratchet teeth 86 formed within hub 87 of the chain wheel 40.

75 The inside of the disk 39' is provided with a flange 88 against which hub 87 is held by means

of a plate 89 secured against the outer surface of both disk 39' and flange 88 by means of a stud 90, which traverses an opening 91 in said plate and is screw-threaded into the end of shaft 38. It should be apparent that when the chain wheel 40 is rotated in a clockwise direction (looking at the outside of said chain) the teeth 86 will engage the dog 81, carrying said dog around with the chain wheel and, of course, rotating the driving disk 39' and shaft 38 on which it is fixed. 10 When the chain wheel 40 is rotated in a counter-clockwise direction the teeth 86 thereof will idle over the dog 81 so that driving disk 39' and shaft 38 will not be rotated.

The complete blowing operation of my improved 15 boiler cleaner may best be described by reference to the diagrams shown in Figs. 19 to 23, inclusive. These diagrams show, reading each figure from left to right, the chain wheel 40 with its internally formed ratchet associated with the driving disk 20 for the blower tube, the valve and stop actuating ratchet, together with the cam for operating the valve, the cam and associated rod 62 or stop bar actuated thereby, and the blower tube driving gear and pinion therefor.

25 In Fig. 19 the parts are shown in their respective positions when the blower is at rest. It will be observed that the valve cam 51 is in its horizontal position so that the valve stem 22 will be raised to allow the valve 23 (not shown in the 30 diagram) to be seated and the cam surfaces 75 and 76 are withdrawn from the pin 77 to allow the stop bar 62 to move to the right, at which time the terminal piece 67 is in the path of and forms an abutment for the stop member 78 projecting 35 from gear 26.

It is, therefore, impossible for the operator to pull on the right-hand side of chain 61 as a clockwise rotation of the chain wheel 40 would tend to rotate the gear 26 counter-clockwise. The 40 operator can, therefore, only pull on the lefthand side of chain 61 to rotate chain wheel 40 in a counter-clockwise direction, as shown in the diagram Fig. 20. When the wheel 40 is rotated in this direction the pawl 43 engages a tooth 42 of 45 ratchet 41, causing the ratchet to rotate with the chain wheel. When the ratchet 41 has rotated through an angle of 90° the cam 51 has also rotated through an angle of 90° and the valve stem 22 has been depressed to open the 50 valve. At the same time the cam surface 76 has forced the stop bar 62 to the left and the pin is resting on the cam surface 75. This movement of the stop bar 62 withdraws the terminal member 67 from the path of the stop 78 so that the 55 gear 26 will now be free to rotate in the direction of the arrow (Fig. 20). The rotation of the ratchet 41 and chain wheel 40 are arrested at the end of the 90° arc by the engagement of lug 73 with the terminal 65 of bar 62. It is thus impossible for the operator to rotate the parts beyond the point at which the valve is fully opened. However, up to this time the blower tube has not moved. In order to rotate the blower tube the operator must now pull on the right-hand side 65 of chain 61 to rotate the chain wheel 40 in a clockwise direction. When the chain wheel 40 is rotated in this direction the internal ratchet teeth 86 will engage with the dog 81, carrying the dog and the driving disk 39' around with the chain 70 wheel 40. Of course, the shaft 38 and pinion 39 will also be rotated because the driving disk 39' is keyed to said shaft.

Since the stop bar 62 has been released from the stop 78 the gear 26 will now be driven by 75

the pinion 39 in a counter-clockwise direction to effect a rotation of the blower tube 11. As we have seen, the valve 20 has previously been opened so that while the blower tube 11 rotates steam 5 will be discharging from it to clean the boiler tubes throughout the entire arc of rotation of the blower tube. This arc of rotation is determined by a second stop 79 spaced a predetermined distance from the stop 78 as determined 10 by the arrangement of the boiler tubes. It is understood, of course, that the spacing of the stops 78 and 79 depends entirely upon the type 15 of boiler and may be varied at will to suit any special type of boiler.

15 Continuing with our description and referring again to Fig. 21, during the first 90° of the rotation of the chain wheel 40 in a clockwise direction, the ratchet wheel 41 will be carried around with the chain wheel 40 under the pressure of 20 the pawl 43 exerted by the tension of spring 45. During this 90° rotation of the ratchet disk 41 the cam surfaces 75 and 76 will move back to their original position (Fig. 19) to allow the 25 stop bar to be forced to the right by the action of spring 68 (Fig. 10) so that the terminal 67 will again come in the path of the stops 78 and 79 so that the rotation of the chain wheel 40 in a clockwise direction can be continued only until the stop 79 impinges on the terminal 67. At this 30 time the blower tube has been rotated through its complete blowing arc and the cleaning operation is finished.

The operator must now close the valve 20, and 35 since he can no longer pull on the right-hand side of the chain 61 he must again pull on the left-hand side of the chain to rotate the chain wheel 40 in a counter-clockwise direction, as shown in Fig. 22. During this rotation the ratchet 41 is rotated with the chain wheel 40 by engagement 40 of the pawl 43 with one of the teeth 42 of the ratchet 41, and the pawl 54 engaging the four-toothed ratchet 49 rotates this ratchet and also cam 51 until the cam is in the position shown (Fig. 22) and the valve stem 22 is allowed to 45 raise and the valve 20 to seat. The arc of rotation is again limited to 90° by the engagement of stop 73 with terminal 65 of bar 62 and the bar has again been moved to the left by the cam surface 76 and is in the position shown (Fig. 22). 50 The terminal 67 of the bar 62 has now been withdrawn from the path of the stop 79 so that the gear 26 will be free to rotate. This rotation is again effected by pulling on the right-hand side of the chain 61, and during the first 90° of 55 the rotation of the wheel 40 the ratchet 41 will also be rotated to withdraw the cam surfaces 75 and 76 from the pin 77 and allow the stop bar 62 to again move to the right so that the terminal 67 will again be in the path of stop 78. As 60 the operator continues to pull on the right-hand chain 61 the gear 26 will continue to rotate until the stop 78 impinges against the terminal member 67 when the gear 26 comes to rest and the blower tube 11 is in its normal starting position 65 for the next subsequent blowing operation.

From the foregoing it is apparent that the 70 operation of my improved soot blower is fool-proof. It is impossible for the operator to operate the parts in any manner except that as described. This insures that the steam supply valve 20 will 75 always be opened first and the blower tube 11 will only be rotated after the valve has been fully opened and the blower tube cannot be restored to its at rest position until after the valve has been fully closed. Even if the operator, after

closing the valve, should neglect to restore the blower tube 11 to its fully closed position this must be done before the next blowing operation can be performed. Thus, there is a definite cycle of operations which must be performed in regular order. 5

In Figs. 24 to 32, inclusive, I show a modification of the invention in which a clutch is substituted for the internal ratchet and driving disk of the main form and two stop bars are utilized 10 instead of one, which stop bars are controlled by a cam carried by the lever which depresses the valve stem. Thus, when the valve stem is depressed to open the valve the stop bar which prevents the blower tube from rotating is simultaneously released, and when the valve stem is allowed to raise to close the valve the stop bar, which has arrested the blower tube at the end of its blowing arc, is simultaneously released. These features will be better understood from a more 15 detailed description of the modified parts shown in Figs. 24 to 32, inclusive.

The ratchet wheel 100 is similar to the ratchet wheel 41 except that it has no corresponding flange 74, and the cam 101 is actuated by mechanism similar to that which actuates cam 51. Instead of the flange 74 with its cam faces 75 and 76, the modified device (shown in Figs. 24 to 32, inc.) is provided with a cam block 102 having oppositely disposed inclined faces 103 and 104, said block 102 being formed on the end of one side 105 of a U-shaped lever 106 pivotally mounted on a pin 107 disposed in the end of an arm 108 projecting from the bracket member 6'. The side 109 of the U-shaped lever 106 corresponds to 25 the lever 57 of the main form of the invention and serves to depress the valve stem 22. The stop bars 110 and 111 are mounted in openings 0, 0' formed in the end of bracket 6' and also openings s, s' in a separate bracket 112. The 30 ends of the bars 110 and 111 adjacent to the cam block 102 are provided with inclined faces 113 and 114, respectively, for engagement with the inclined faces 103 and 104 of the cam block 102. The opposite ends of the stop bars 110 and 111 35 are provided with inclined faces 115 and 116, respectively, for engagement with inclined faces 117 and 118 of stop members 119 and 120 on gear wheel 26'. The hub 121 of chain wheel 40' is provided with an outwardly presented clutch 40 member 122 for cooperation with clutch member 123 formed on collar 124 keyed to shaft 38'. There is 90° of play between the clutch members 122 and 123 so that the chain wheel 40' may be 45 rotated 90° to the left to actuate the valve 20 by depressing the stem 22 without imparting any motion to the shaft 38'. It will be remembered from the description of the main form that the valve is opened by the rotation of the cam 101 which depresses the U-shaped lever 106, which, 50 of course, moves the cam block 102 downwardly to withdraw the inclined face 103 from the inclined face 113 and release the stop bar 110 so that it may be moved forwardly or away from gear 26' (see diagram Fig. 33). 55

When the chain wheel 40' has been moved through an angle of 90°, the stop 125 will engage lug 126 projecting from bracket member 6' to prevent further rotation of the hand wheel and, of course, cam 101. The 90° of play between 70 clutch members 122 and 123 permits this rotation of the wheel 40' to open the valve without imparting any motion to shaft 38' or blower tube 11. The operator may now manipulate the operating chain to rotate the wheel 40' in the op- 75

posite direction, the first 90° of which rotation takes up the play between clutch members 122 and 123, and stop 125' impinges on lug 126 to arrest further rotation of ratchet wheel 100. A continuation of the rotation of chain wheel 40' causes rotation of shaft 38' to also impart rotation to gear 26'. Since the outer end of stop bar 110 has been released from the engagement with cam block 102, the stop member 119 on the gear 10 26' will slide this stop bar 110 forwardly as it moves past the inclined face 115 at the end thereof. As the same block 102 moves downwardly to release stop bar 110, the inclined face 104 thereof will engage inclined face 114 of 15 stop bar 111, forcing the bar 111 backwardly into the path of stop 120 on gear wheel 26' so that as the operator continues to rotate the chain wheel 40' in the direction to also rotate the blower tube 11, the stop 120 will approach the end of 20 stop bar 111 and finally impinge against the same to arrest any further rotation of the gear 26' and blower tube 11. The complete blowing arc has now been traversed and the next operation is, of course, to close the valve.

25 This is done in the same manner that the valve is opened, namely, by rotating the chain wheel 40' in the direction indicated by the arrow (Fig. 25), which also rotates the ratchet wheel 100 and cam 101 to restore the valve stem 22 and lever arm 109 to the position shown in Fig. 26. As the lever arm 109 is restored to this position the arm 105 is also raised to move the cam block 102 upwardly, causing the bar 110 to be slid toward the gear 26', and to allow the bar 111 to be moved by 30 stop member 120 forwardly to permit said stop to pass end 116 of stop bar 111. The valve now having been closed the operator again rotates the hand wheel in a clockwise direction to rotate the gear wheel until stop 119 again impinges on 35 the end of stop bar 110, at which time the blower has been restored to its at rest position.

Having described my invention, I claim:

1. A boiler cleaner comprising a soot blower tube, a steam supply pipe, a valve between said 45 supply pipe and tube for controlling the flow of steam to said tube, mechanism for actuating the valve, mechanism for rotating the blower tube, a single rotatory means for operating the valve actuating mechanism and the tube rotating mechanism, means associated with said rotatory means effective on the valve operating mechanism only when said rotatory means is rotated in one direction, and means associated with the rotatory means effective on the tube rotating mechanism 50 only when said rotatory means is rotated in the reverse direction.

2. A boiler cleaner comprising a soot blower tube, a steam supply pipe, a valve between said supply pipe and tube for controlling the flow of steam to said tube, mechanism for actuating the valve, mechanism for rotating the blower tube, a single rotatory means for operating the valve actuating mechanism and the tube rotating mechanism, means associated with said rotatory means effective on the valve operating mechanism only when said rotatory means is rotated in one direction, means associated with the rotatory means effective on the tube rotating mechanism only when said rotatory means is rotated in the reverse direction, and a stop device cooperating with the tube rotating mechanism to confine the movement of the tube to a definite arc, and means actuated in synchronism with the valve actuating mechanism for releasing said stop device from the tube rotating mechanism.

3. A boiler cleaner comprising a soot blower tube, a steam supply pipe, a valve between said supply pipe and tube for controlling the flow of steam to said tube, mechanism for actuating the valve, mechanism for rotating the blower tube, 5 a single rotatory means for independently operating the valve operating mechanism and the tube rotating mechanism, a stop device operatively associated with the blower tube to confine the rotation thereof to a predetermined arc, and 10 means actuated in synchronism with the valve operating mechanism for moving said stop device to release the blower tube from the confinement of said arc.

4. A boiler cleaner comprising a soot blower 15 tube, a steam supply pipe, a valve between said supply pipe and tube for controlling the flow of steam to said tube, mechanism for actuating the valve, mechanism for rotating the blower tube, a single rotatory means for operating the valve 20 actuating mechanism and the tube rotating mechanism, means associated with said rotatory means effective on the valve operating mechanism only when said rotatory means is rotated in one direction, means associated with the ro- 25 tatory means effective on the tube rotating mechanism only when said rotatory means is rotated in the reverse direction, and a stop device interposed between the blower tube and rotating mechanism therefor to confine the movement of 30 said tube to a predetermined arc, and means actuated in synchronism with the valve actuating mechanism to withdraw said stop device from such interposition.

5. A boiler cleaner comprising a soot blower 35 tube, a steam supply pipe, a valve between said supply pipe and tube for controlling the flow of steam to said tube, mechanism for actuating the valve, mechanism including a gear for rotating the blower tube, a single rotatory means for 40 independently operating the valve operating mechanism and the tube rotating mechanism, spaced lugs on said gear, a reciprocable stop member disposed in the path of travel of said lugs, means for holding said stop member in said 45 path, and means actuated in synchronism with the valve actuating mechanism for moving said stop member out of the path of said lugs.

6. A boiler cleaner comprising a soot blower tube, a steam supply pipe, a valve between said 50 supply pipe and tube for controlling the flow of steam to said tube, mechanism for actuating the valve, mechanism for rotating the blower tube, an operating wheel, driving means between the wheel and blower tube rotating mechanism, said 55 driving means being effective on rotation of operating wheel in one direction, an oscillating member between the wheel and valve actuating mechanism, said oscillating member being effective on the valve operating mechanism on rotation of 60 operating wheel in the opposite direction, a movable stop device for engagement with the tube rotating mechanism, and means on the oscillating member for controlling the movement of the stop 65 device into and out of engagement with the tube rotating mechanism.

7. In a soot blower comprising a rotatable blower tube, a steam supply pipe, a valve between the tube and supply pipe, and an operating head 70 for the valve and blower tube, said operating head comprising means for operating the valve, means for rotating the blower tube, and a single actuating wheel associated with both the valve operating means and blower rotating means, 75

mechanism for coupling the wheel and valve operating means when the wheel is rotated in one direction, and mechanism for coupling the wheel and blower rotating means when the wheel is operated in the opposite direction, locking means effective on the blower tube to prevent

rotation thereof, means co-acting with the valve operating means for moving said locking means to unlocked position on opening the valve and means for moving said locking means to locking position after rotation of the blower tube.

LEO JNO. BAYER.
